UNITED STATES PATENT OFFICE.

ROYAL L. BOULTER, OF LOS ANGELES, CALIFORNIA.

TELEGRAPH-KEY.

1,110,373.

Specification of Letters Patent. Patented Sept. 15, 1914.

Application filed September 2, 1913. Serial No. 787,696.

To all whom it may concern:

Be it known that I, ROYAL L. BOULTER, a citizen of the United States, residing at Los Angeles, county of Los Angeles, and State of California, have invented certain new and useful Improvements in Telegraph-Keys, of which the following is a specification.

This invention relates to telegraph keys.

The present invention relates to that class 10 of telegraph keys known as "transmitters" or "vibrators" which employ a vibratory reed in connection with a key for the purpose of automatically making the dots to relieve the operator of the repeated finger 15 and wrist movements necessary with the ordinary telegraph key when making a series of dots. This class of transmitter also employs a separate key for forming dashes. The two keys are, in most transmitters at 20 present known to the art, arranged for movement laterally or sidewise, as contradistinguished from the up and down movement of the old type of telegraph key, and they are particularly designed for sending 25 messages rapidly with a minimum effort on the part of the operator, but are particularly useful to operators having writer's cramp or telegrapher's paralysis.

The present invention is an improvement 30 on the telegraph key set forth in my application Serial No. 714794, filed August 13, 1912.

Before my earlier invention above referred to, transmitters of this type, while 35 superior in many respects to the old style Morse key, have been incapable of such adjustment as to adapt them for both fast and slow work and for use on both long and short lines; they have been subject to the 40 involuntary formation of what operators term "split" dots owing to the quick vibrations of the vibrator or reed which occurs before the lever is released, particularly in letters of the alphabet having but one dot 45 such as "A" and "N"; and they have usually also been complicated, have occupied considerable space and are liable to derangement.

The present invention has for its object 50 the provision of a transmitter or vibrator telegraph key which will be simple, compact, strong, durable, susceptible of any desired adjustment of the contacts, and particularly those used for forming dots.

55 Another object of the invention is the provision, in a telegraph transmitter or vi-

brator, of novel, adjustable dot producing means combined with a vibrator in a new manner and susceptible of adjustment within a wide range which will be adapted to 60 make a single dot as in the ordinary or Morse key, the vibrator having nothing to do with the making of a single dot, and to produce a plurality of dots automatically without possibility of sending split dots. 65

The dot making mechanism embodies means whereby when the dot key is operated, the electrical circuit is closed through the contacts except when periodically opened automatically by the vibrations of the vibrator due to the new contact employed and the new manner in which the vibrator cooperates with said contact, whereby the circuit is automatically and regularly opened by the vibrations of the vibrator with short 70 intermittent interruptions. This construction results in closing of the circuit for a maximum of time and the sending of the longest and heaviest dots possible, so far as I am aware, in any vibratory transmitting 75 80 telegraph instrument. At the same time, the construction is such that a single dot is formed as with an ordinary Morse key.

The instrument is adapted for slow or fast work and on either short or long circuits. 85

The present invention is designed to simplify, cheapen, and lighten the construction of the vibratory reed, and the tapping mechanism which is characteristic of the invention of my application Serial No. 714794, to thereby render the vibratory reed more sensitive, easier to finger and adaptable for finer adjustment with less liability of derangement than with my earlier invention 95 set forth in application Serial No. 714794.

The present invention also represents improvements in the pivots or trunnions of both the dot and dash keys and the spring tensioning means therefor, whereby either 100 a relatively heavy or light tension may be obtained.

An embodiment adapted to carry out the objects of the present invention and its improvements is set forth fully hereinafter 105 and the novel features are recited in the appended claims.

In the accompanying drawings: Figure 1 is a plan view of the complete instrument; Fig. 2, a bottom view thereof; Figs. 3 and 110 4, opposite side elevations; Fig. 5 a perspective of the vibrator, its frame, and

operating key alone; Fig. 6, a section on line 6—6, Fig. 1 through the bob or weight; Fig. 7, a section on line 7—7, Fig. 1; Fig. 8, a section on line 8—8, Fig. 1; Fig. 9, a section on line 9—9, Fig. 1; Fig. 10, a horizontal section through the standards, showing the tension adjusting screws for the keys, and Fig. 11, a horizontal section through the joint connecting the keys to their frames and springs.

The base 1 is preferably of metal to form a part of the circuit, one of the binding posts 2 being connected thereto, the other binding post 3 being insulated therefrom. 15 The adjustable dash contact 4 and the adjustable dot contact 5 are in circuit with the binding post 3 by the connections 6. A circuit closer is shown at 7.

The open frame of the dot lever is shown 20 at 8 and that of the dash lever at 9. The said levers have respective bearings 10 and 11 which receive the points of pivots 12 and 13 which are carried by studs shown respectively at 14 and 15, the said studs passing loosely through the standards 16 and 17 which are connected to the base 1 by nuts 18 and are coupled together by screws 19 which have spacing members 20 interposed between the standards.

25 The studs 14 and 15 are provided with clamping nuts 21, whereby they may be clamped to the standards after adjustment. This manner of pivoting the levers enables them to be delicately adjusted so that there 30 is no lost motion at the pivots and it at the same time insures the disposition of the dot and dash contacts so that they will operate with those on the base.

The frames 8 and 9 are open as shown 40 at 22. Disposed in the open portions are leaf springs 23 and 24 which have their ends set in recesses 25 and secured to the frames 8 and 9 by the same screws 26 which fasten the respective finger pieces or keys 45 27 and 28 to the frames 8 and 9.

The finger pieces have parts received in the recesses 25 and these finger pieces also overlap extensions on the frames 8 and 9 and likewise abut the ends of said frames. 50 To the respective standards are secured brackets 29 and 30 in which are journaled screws 31 and 32. The respective screws are threaded through fingers 33 and 34 so that by turning the screws the fingers will move 55 in one direction or the other. These fingers are prevented from falling and are maintained in upright position by engagement with the respective brackets against which they slide. Interposed between the

60 fingers and the respective leaf springs 23 and 24 are coil springs 35 and 36 whose ends engage openings in the fingers and the said leaf springs. By turning the thumb adjusting screws, the fingers are moved and 65 the coil springs placed under greater or

lesser tension, which in turn is imparted to the leaf springs and by them to the frames 8 and 9, whereby the reactive tension on the key levers may be regulated to suit the touch of the operator. The combination of 70 the coil springs with the leaf springs affords a greater and superior tension and cushioning effect on the key levers than would be the case if the leaf springs were omitted and by reason of the fact that these 75 leaf springs are only connected to the frames 8 and 9 at the outer ends of said leaf springs or at points distant from the engagement of the coil springs with the leaf springs, the tension is imparted by a yielding leverage, 80 as it were, which, acting upon the key levers at points relatively distant from the pivots of said key levers, affords any desired tension without having to position the coil springs or the adjusting screws where they 85 would interfere with the operator's fingers.

The dash lever or frame is arrested by an adjustable stop 37 which limits its play due to the spring tension. The dot lever is arrested when its key is fingered, by an adjustable screw 38.

The vibrator or reed 39 is of inherently springy or resilient material, being provided or ribbon spring 43 which is inherently parts 41 which are connected to the dot 95 lever frame 8, preferably by insertion in a split portion thereof and by riveting thereto at 42.

Secured to the dot lever frame 8 and preferably located between the parts 41 is a leaf or ribbon spring 43 which is inherently 100 flexible or resilient and which tends to flex toward the dot contact 5. Secured to this spring cushion 43 is a contact frame or head 44 which has a platinum contact 45 105 adapted to engage contact 5, the said frame straddling the vibrator and carrying an adjustable tapping or anvil screw 46 which, due to the flexing tendency of the leaf spring 43 is normally in engagement with 110 the vibrator. Consequently, when the dot key is tapped or moved lightly, the vibrator and the ribbon or leaf spring and the tapping member move as an entirety and but a single dot is formed, but if the pressure of 115 the thumb is retained, the sudden arrest of the vibrator by the engagement of the contacts 5 and 45 sets the vibrator into vibration and the tapping action which ensues causes the said contacts to be automatically 120 and periodically separated, thereby producing a plurality of dots, the number of which is determined by the length of time the dot key is held.

To regulate the vibrations of the vibrator, 125 I provide an adjustable weight or bob 47 consisting of two knurled nuts, one of which carries a screw-threaded stem 48 which passes through the slot 40 and the other having a screw-threaded engagement with said 130

stem. By loosening these nuts, the bob may be slid along the vibrator and re-clamped at the desired point.

To bring the vibrator to a stop or rest 5 when the dot key is released, I provide a back stop 49 consisting of pillars rising from the base 1 and a bar 50 connecting them and provided with a fiber or insulating strip 51 against which the stem of the bob 10 strikes. The provision of this non-metallic member 51 deadens the sound of the arrest of the vibrator.

The forefinger is used to operate the dash key and the thumb the dot key, the movement of the hand being in a general lateral direction. When a dash is to be formed, the dash key is pressed. When a single dot is to be formed, the dot key is tapped or pressed with the thumb, whereupon the vibrator and the tapping device move as an 20 entirety for the formation of a single dot. If, however, a plurality of dots are to be formed, the pressure of the thumb is maintained, whereupon the inertia imparted to 25 the vibrator causes the latter to be set into vibration which is more or less slow or fast according to the position of the bob.

As a result of the present construction, I am able to produce, so far as I am aware, 30 the longest and heaviest dots which it has been possible to make on a transmitter key, as the circuit is closed for a maximum period of time during the travel of the vibrator and I thereby avoid the formation of 35 split dots, but at the same time gain all the advantages of the formation of a single dot without any danger of splitting the dot in that event.

It will be observed that in the formation 40 of dots, the operation is different from that in vibrating transmitters heretofore known, as the movement of the key on the application of pressure thereto at once effects an initial positive engagement of the dot sending contacts.

Having thus described my invention, what I claim as new and desire to secure by Letters Patent, is:—

1. In a telegraph transmitter, the combination with an operating key, of a vibrator 50 connected thereto and movable therewith, a leaf or ribbon spring connected to and movable with the key, whereby said key,

vibrator and leaf or ribbon spring are adapted to move together as an entirety, a contact carried by the leaf or ribbon spring, and means carried by said leaf or ribbon spring adapted to coöperate with the vibrator and arranged and adapted so that said vibrator is adapted to deliver taps 60 thereon.

2. In a telegraph transmitter, the combination with a pivoted key lever, of a vibrator blade secured thereto and movable therewith and provided with an opening, a 65 ribbon or leaf spring secured to the key lever and disposed within the opening of the vibrator blade, a tapping head carried by a free part of the leaf or ribbon spring and loosely embracing a portion of the vibrator blade, a contact carried by said tapping head, and a tapping member carried by said head and adapted to coöperate with the vibrator, whereby the vibrator is adapted to impart taps to said head. 75

3. In a telegraph transmitter, the combination with an operating key, of a leaf spring secured thereto and carried thereby and having a free part, and adjustable means for tensioning the free part of said 80 spring to thereby yieldingly hold the operating key.

4. In a telegraph transmitter, the combination with an operating key, of a leaf spring secured thereto and having a free 85 part, a coil spring coöoperating with the free part of said leaf spring, and an abutment for said coil spring.

5. In a telegraph transmitter, the combination with an operating key, of a leaf 90 spring secured thereto and having a free part, an adjustable finger, and a coil spring interposed between said finger and a free part of said leaf spring.

6. In a telegraph key, the combination 95 with a key lever having pivot sockets, of a standard, studs rockably carried by said standards and provided with trunnions entering the sockets aforesaid, and nuts for clamping said studs in different positions. 100

In testimony whereof, I hereunto affix my signature in presence of two witnesses.
